DESIGN FOR A HYGROMETER

Benjamin E. Lawrence, Chicago, Ill.

Application November 10, 1944, Serial No. 116,272

Term of patent 3½ years

(Cl. D52—7)

To all whom it may concern:

Be it known that I, Benjamin E. Lawrence, a citizen of the United States, residing in Chicago, in the county of Cook and State of Illinois, have invented a new, original, and ornamental Design for a Hygrometer, of which the following is a specification, reference being had to the accompanying drawings forming part thereof:

Fig. 1 is a front perspective view of a hygrometer showing my new design;

Fig. 2 is a top plan view; and

Fig. 3 is a front elevational view thereof.

I claim:

The ornamental design for a hygrometer, substantially as shown.

BENJAMIN E. LAWRENCE.
